UNITED STATES PATENT OFFICE.

HAROLD M. BECHER, OF BROOKLYN, NEW YORK.

DESIGN FOR A DYED FUR.

Application filed September 17, 1925. Serial No. 14,806. Term of patent 14 years.

To all whom it may concern:

Be it known that I, HAROLD M. BECHER, a citizen of the United States of America, residing at Brooklyn, in the county of Kings and State of New York, have invented a new, original, and ornamental Design for a Dyed Fur, of which the following is a specification, reference being had to the accompanying drawing, forming part thereof.

The figure is a plan view of a piece of fur showing my new design. The heavy cross-hatching indicates contrasting color and illustrates the design forming the invention.

I claim:

The ornamental design for a dyed fur, as shown and described.

HAROLD M. BECHER.
